Primary Examiner — Prabhakar G Deshmukh*(74) Attorney, Agent, or Firm* — Wolf, Greenfield & Sacks, P.C.(57) **CLAIM**

The ornamental design for a cabinet lock, as shown and described.

DESCRIPTION

FIG. 1 is a top, front, left side perspective view of a cabinet lock showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines illustrate unclaimed portions and form no part of the claimed design.
